UNITED STATES PATENT OFFICE.

HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

CALLING DEVICE.

1,264,366.

Specification of Letters Patent.

Patented Apr. 30, 1918.

Application filed October 13, 1916. Serial No. 125,396.

To all whom it may concern:

Be it known that I, HENRY P. CLAUSEN, a citizen of the United States, residing at Mount Vernon, in the county of Westchester 5 and State of New York, have invented certain new and useful Improvements in Calling Devices, of which the following is a full, clear, concise, and exact description.

This invention relates to improvements in 10 calling devices, and more particularly to impulse transmitters for automatic and semi-automatic telephone systems.

The satisfactory operation of the central office apparatus in an automatic telephone 15 system is dependent upon the normal operation of the substation calling device or impulse transmitter. In many types of calling devices, a manually operable member is operated by the subscriber, once for each 20 digit of the number called, and in returning to normal permits the mechanism to send out impulses corresponding to the digit for which the device is operated. The rate at which the manually operable member returns to normal governs the rate at which 25 the signaling impulses are sent, and for the successful operation of the central station apparatus this rate should not be altered by the subscriber. It sometimes happens, however, 30 that normal operation of the calling device is interfered with by the subscriber's forcing the manually operable member in its movement backward to its normal position, instead of allowing it to return at its natural rate. This is particularly liable to 35 occur when the desired number has two successive digits which are the same; because the subscriber is then liable to leave his finger in engagement with the selected 40 finger-hold and to force the manually operable member backward to its normal position. It may also happen that the complete return of the manually operable member to its normal position is prevented by 45 the subscriber's placing his finger in engagement with a finger-hold before the manually operable member has completed its return movement.

The object of the present invention is to 50 provide a new and improved calling device in which the return movement of the manually operable member cannot be hastened; and in which means is provided for deterring the subscriber from actuating the 55 manually operable member a second time

until the return movement resulting from a previous actuation has been completed.

In general, a calling device embodying the present invention is characterized by a connection between the manually operable 60 member and the shaft driven thereby which permits lost motion of the former with reference to the latter in the direction opposite to the direction of operating movement of the former; and is also characterized by 65 means for hiding the symbols corresponding to the finger-holds while the manually operable member is in an off-normal position. These features may of course be used either together or separately. 70

The present invention is applicable to calling devices of many types, and is not to be considered as limited in its application to a calling device of the type herein-after described, since this type is selected 75 merely for the purpose of illustration.

In the drawing, Figure 1 is a plan view of a calling device having the present invention embodied therein, certain parts being broken away; Fig. 2 is a side elevation 80 thereof, some parts being broken away and some shown in cross section; and Fig. 3 is a plan view of said calling device showing the manually operable member in an off-normal position and the symbols hidden. 85

Referring to the drawing, the interior mechanism of the calling device is inclosed within the casing 4. As this mechanism forms no part of the present invention, it need not be described further than to say 90 that it is operated by the shaft 5 which projects from said casing. Rotatably mounted upon the end of the shaft 5 beneath the head 6 is the manually operable member 7. The manually operable member 7 is provided with a plurality of finger-holds in 95 the form of holes. Symbols carried on a suitable member or upon top of the casing 4 are arranged to coöperate with said finger-holds in a well-known manner. The connection between the manually operable member 7 and the shaft 5 permits lost motion of the former with reference to the latter in the direction opposite to the direction of operating movement of the former. This 100 connection comprises a slotted member 10 mounted on and rigidly secured to the shaft 5. The slot in the member 10 is concentric with the shaft 5, and the pin 11, extending from the back of the member 7, projects 105 110

into said slot. This pin and slot connection between the member 7 and the shaft 5 permits relative angular movement of these elements; but a spring 21 of the form shown, 5 secured at one end to the slotted member 10 and at the other end to the pin 11 tends to hold these parts in the relative position shown in Fig. 1. Above the symbols is a movable plate 12 having openings through 10 which these symbols may be seen. This plate is capable of limited angular movement, from the position in which it is shown in Fig. 1 to the position shown in Fig. 3, under the influence of the spring 13, attached 15 at one end to a lug 14 on the inside of the casing 4 and at its other end to a lug 15 projecting from the plate 12. Projecting from the edge of the plate 12 is another lug 16, which passes through a slot 20 in the hub casing 17 projecting from the main casing 4 as shown in Fig. 2. The lug 16 projects into the path of a lug 18 on the edge of the slotted member 10. In the normal position of the calling device, the lug 25 18 is in engagement with the lug 16 and holds the latter at one end of the slot in the hub casing 17; but when the calling device is in an off-normal position, the lug 18 moves away from the lug 16 and permits 30 the latter to move to the other end of said slot under the influence of the spring 13 upon the plate 12. A stop 20 is shown secured to the casing 4 and arranged to engage the finger of the person operating the 35 device and to thus limit the movements of the manually operable member 7, in the well-known manner.

The calling device above described is operated in the usual manner by placing a 40 finger in engagement with the finger-hold through which is visible the numeral or character corresponding to the digit for which it is desired to transmit impulses, and by rotating the manually operable member 45 7 in the direction of the arrow until the finger engages the stop 20. The finger is then removed and the manually operable member returns to normal position under the influence of the impulse sending mechanism inclosed within the casing 4. In the 50 normal operation of the device, the pin 11 remains at the end of the slot in the member 10, as shown in Fig. 1. If, however, the subscriber does not remove his finger 55 from engagement with the finger-hold after his finger has engaged the stop 20, and if he tries to force the manually operable member in its return movement, the force so exerted will be expended in placing the 60 spring 21 under increased tension by the movement of the pin 11 in the slot of the member 10. The spring 21 is so designed that the turning force which it is thus made to exert upon the member 10 and the shaft 65 5 does not injuriously affect the rate at

which the mechanism returns to its normal position. Of course, while the manually operable member 7 is thus forced backward from its normal position with reference to the slotted member 10, the latter continues 70 to return to its normal position. In other words, forcing back the manually operable member does not artificially accelerate the return movement of the impulse sending mechanism of the calling device. Of course 75 the slot in the member 10 may be of any desired length. In practice, a slot of the length shown will be usually sufficient to prevent backward forcing.

As hereinbefore explained, the plate 12 is 80 maintained in its normal position shown in Fig. 1 by engagement of the lug 18 with the lug 16; and said plate moves into the position shown in Fig. 3 when the lug 18 moves away from the lug 16, which occurs 85 when the device is moved to an off-normal position. By this movement of the plate 12 and the member carrying the symbols with reference to one another, the symbols are obscured during the movement of the manually operable member 7 back to its normal 90 position, but are re-displayed immediately when the normal position is reached. By so hiding the symbols during the return movement of the device, the likelihood of the 95 subscriber's prematurely inserting his finger in a finger-hold is reduced to a minimum, since it would be extremely unnatural to insert the finger in a finger-hold in connection with which no symbol is visible. The 100 complete return of the manually operable member to its normal position is thus assured. Moreover, by thus requiring a subscriber to watch for the re-display of the symbols at each actuation of the calling device, a certain time interval is insured between successive actuations of the device, which is desirable in connection with certain kinds of automatic telephone systems. 105

What is claimed is:

1. In a calling device, a manually operable member, an operating shaft driven thereby, a connection between said member and said shaft permitting lost motion of the former with reference to the latter in 115 the direction opposite to the direction of operating movement of the former, a member carrying symbols corresponding to said finger-holds, and means for hiding said symbols while said manually operable member is in an off-normal position. 120
2. In a calling device, a manually operable member having finger-holds, an operating shaft driven thereby, a connection between said member and said shaft permitting lost motion of the former with reference to the latter in the direction opposite to the direction of operating movement of the former, a member carrying symbols corresponding to the finger-holds, a member 125 130

having openings through which the symbols are normally visible, and means for moving said last-named member and said symbol-carrying member with reference to one another so as to hide said symbols while said manually operable member is in an off-normal position.

3. In a calling device, a manually operable member having finger-holds, an operating shaft driven thereby, a slotted member carried by said operating shaft, a pin carried by said manually operable member and extending into the slot of said slotted member, a spring which tends to maintain said pin at the forward end of said slot, a member carrying symbols corresponding to the finger-holds, a movable member having openings through which the symbols are normally visible, a spring tending to move said last-named member into the position in which it hides said symbols, and lugs on said movable member and said slotted member which coöperate when said manually operable member is in its normal position and maintain said movable member in the position in which said symbols are visible.

4. In a calling device, a manually oper-

able member, an operating shaft driven thereby, and a lost motion connection between said member and said shaft permitting at all times motion of the former with reference to the latter in the direction opposite to the direction of operating movement of the former.

5. In a calling device, a manually operable member having finger-holds, a member carrying symbols corresponding to said finger-holds, and means for hiding the symbols while said manually operable member is in an off-normal position.

6. In a calling device, a manually operable member having finger-holds, a plate carrying symbols corresponding to said finger-holds, a plate having openings through which the symbols are normally visible, and means for moving said plates with reference to one another so as to hide the symbols when said manually rotatable member is in an off-normal position.

In witness whereof, I hereunto subscribe my name this 11th day of October, A. D. 1916.

HENRY P. CLAUSEN.
